[57] CLAIM

The ornamental design for a animal dry food scoop, as shown and described.

DESCRIPTION

FIG. 1 is a perspective view taken from the top and front of the animal dry food scoop, showing our new design;

FIG. 2 is a top plan view thereof;

FIG. 3 is a right side elevation view thereof;

FIG. 4 is a rear elevation view thereof; and,

FIG. 5 is a front elevation view thereof.

The unshown side is a mirror image of the side shown in FIG. 3.
